UNITED STATES PATENT OFFICE.

SAHATIEL G. MANDALIAN, OF NORTH ATTLEBORO, MASSACHUSETTS.

DESIGN FOR A BAG-TOP.

59,851.

Specification for Design.

Patented Nov. 29, 1921.

Application filed January 3, 1921. Serial No. 434,806. Term of patent 14 years.

To all whom it may concern:

Be it known that I, SAHATIEL G. MANDALIAN, a citizen of the United States, residing at North Attleboro, in the county of Bristol and State of Massachusetts, have invented a certain new, original, and ornamental Design for a Bag-Top, of which the following is a specification.

In the accompanying drawing which forms a part of this specification the figure is a perspective view of a bag top embodying my new design, and showing a portion of a suspension chain attached thereto partly broken away.

An essential feature of this design is the presence of ornamentation upon the side face of the top as well as upon the upper surface thereof.

I claim:

The ornamental design for a bag top as shown.
